APPARATUS FOR MARKING STRANDS

John W. Olson, Hastings on Hudson, N. Y., assignor to Anaconda Wire and Cable Company, New York, N. Y., a corporation of Delaware

Application September 28, 1937, Serial No. 166,079

4 Claims. (Cl. 101—36)

This invention relates to improvements in devices for applying lettering to strands and more particularly relates to apparatus adapted to practice the method of marking disclosed in my co-pending application Ser. No. 164,474, filed September 18, 1937 which is especially directed to a novel type of identification for electric conductors. Electric conductors as commonly made are frequently provided with exterior layers of wax-like finishing materials which tend to lubricate the surface of the conductors thus allowing them to be easily pulled into conduits and also prevent sticking to other wires with which they may come in contact. Similarly the finish employed may be chosen for its resistance to burning and materials such as stearine pitch are commonly used to impart a degree of noninflammability to the insulation. Quite frequently the same conduit will carry a considerable number of wires constituting different circuits and for ease of installation, it is essential that these be readily identified one from another. In the past various colored layers of lacquer or enamel have been placed over stearine pitch to provide a color coating and still retain a degree of flame resistance but the number of conductors which can be identified in this manner is limited by the number of available colors which are readily distinguishable from each other and it has generally been found that confusion results if more than five colors are used.

In my aforementioned application I have disclosed a method of marking strands which are finished with a layer of bituminous or wax-like compounds in which indentations in the surface of the strand are partially filled with pigments dispersed in a base compatible with the bituminous material. The pigment is transferred to the indentations from a precoated strip of paper or similar material and it has been found possible to design apparatus for the application of this type of marking in which the amount of pigmented strip required for marking is greatly decreased. It is the chief object of this invention to provide apparatus for the production of marked electrical conductors which employs a minimum amount of marking strip. Another object of this invention is to provide a machine capable of printing wire at high speeds, generally in the range of 650' per minute. A still further object is the provision of marking apparatus which involves a minimum number of moving parts and which places but slight stress on the strip. Further objects and advantages of this invention will be disclosed from the following detailed description

when read in connection with the accompanying drawings.

Referring to the drawings in which like numerals denote similar parts:—

Figure 1 is an elevation of apparatus for marking strands made in accordance with this invention, certain parts having been broken away and illustrated in section to clearly reveal the construction. 5

Figure 2 is a section of an electric conductor 10 which has been marked with the apparatus illustrated in Figure 1.

Figure 3 is an elevation of the conductor illustrated in Figure 2.

Figure 4 is a section of the machine shown in 15 Figure 1 taken at the plane A—A.

Figure 5 is a detailed elevation, certain parts having been broken away, of the marking wheel and idler pulley of the mechanism illustrated in 20 Figure 1.

Referring to Figure 1, the rotary cradle 11 which is fitted with a marking wheel and a supply of pigmented strip is provided with gudgeons 42 at both extremities which terminate in the inner raceway 43 of the bearings 13. The outer raceways of the bearing 13 are fitted into appropriate recesses in the sideplates 12. As indicated in the drawings the cradle consists of three main portions, a marking disc 14 and two yokes 44 and 45 which carry the supply and take-up spools respectively. 30

It is to be understood that this device will ordinarily form a portion of a finishing line such as is commonly used for the application of compounds to the wire during manufacture. When 35 this is the case the strand 19 will be drawn between the marking wheel 14 and the idler pulley 20 by the capstan or reel upon which the finished wire is coiled. The idler pulley 20, mounted in the fork 21 which is pivoted about the rod 22, exerts 40 sufficient pressure on the moving strand 19 to rotate the cradle 11. The compression spring 23 may be adjusted by the wingnut 24 to provide the correct amount of force. In some cases, however, it may be desirable to employ the marking mechanism as a driving unit to propel the wire and in this case the marking wheel 14 or idler pulley 20 45 may be rotated by a belt or suitable electric motor.

The supply of precoated strip is carried in the 50 yoke 44 in the form of a roll 17 mounted on an axle 25. The width of the strip should be slightly greater than the length of the legend which is to be impressed on the strand and the length of the strip should be sufficient to provide continuous 55

operation for a period of at least one working shift. It has been found that a roll of paper four inches in diameter containing approximately one thousand feet will run without replenishing for 5 eight hours since only six feet of strip are required to mark a thousand feet of strand at ten inch intervals. By ordinary methods where the paper and the strand are moving in the same direction, one thousand feet of strip would be necessary for each thousand feet of wire.

A satisfactory composition for producing markings of pleasing appearance may be made from the following ingredients:—

	Grams
15 Paraffin wax (melting point 140° F.)	50
Carnauba wax	15
Turpentine	112
Carbon tetrachloride	112
Light mineral oil	1
20 Extra fine copper powder	285

All the above materials are mixed together, slowly heated to approximately 200° F. and are maintained at this temperature until a homogeneous mass is obtained. When cool the mixture is quite viscous and is ready for application to paper or cloth strip in accordance with methods well known in the art. When applied in a thin layer the solvents evaporate leaving a film of pigment dispersed in a wax-like base which is relatively hard and possesses a moderate degree of resistance to rubbing. It is of course possible to substitute other pigments such as titanium dioxide, umber, French ochre or cadmium orange for the copper dust used in the above illustration, 30 the quantity of coloring matter used being dependent on the degree of opacity required.

When drawn from the supply roll 17 by the take-up spool the strip is carried across the face of the marking wheel 14 which consists of a marking disc 39 carrying raised type 15 and two flange wheels 38. The strip 26 is brought across the surface of the marking type 15 and then after the impression has been made in the wire, is rolled upon the take-up spool 18, which is affixed to the ratchet wheel 27. A cam 28 is mounted on the inner surface of the side plate 12 so as to depress the plunger 29 during that portion of rotation when the strip 26 is not in contact with the strand 19. Depression of the plunger 29, held 45 normally in extended position by the compression spring 30, actuates the pawl 31 in a small arc about its axis 32. In this manner the take-up spool 18 is rotated sufficiently during each revolution of the marking wheel 14 to expose an unused portion of the pigmented strip 26 to the wire at a time when the strip and strand are not in contact. Details of the marking wheel showing the 55 relationship between the idler pulley 20, strip 26, the strand 19, and the marking disc 39 are further 60 illustrated in subsequent drawings.

An insulated electric conductor, typical of the strands which may be marked with this apparatus is illustrated in Figure 2. As shown, conductor 32 is covered with an extruded layer of rubber 33 which is in turn protected with a fibrous braid 34. A layer of flameproofing material 35, such as stearine pitch, is applied over the braid so that the completed conductor will not support combustion. In order to overcome the stickiness of the flameproofing layer, an outer coating of wax 36 is applied and it is in this layer that the indentations 37 are made which are partially filled with pigmented compound 38, transferred to the 75 conductor under pressure from the strip 26.

As illustrated in Figure 3 the markings would commonly comprise the name of the manufacturer and the maximum voltage for which the wire was intended and, in addition, it has been found practical to vary the color used in marking to provide a method of identifying the various branches of an electric circuit.

As will be seen from Figure 4, the strand 19 is subjected to considerable pressure when drawn between the idler pulley 20 and the marking wheel 14. The flange discs 38 are secured to their respective yokes 44 and 45 and the marking disc 39 is held between them by suitable bolts 40. The strip 26 is maintained in position between the surface of the marking indicia 15 and the strand 19 by the slots 41 placed near the outer portion of the flange discs 38 as shown in Figure 5. For purposes of clarity the strip 26 as illustrated is not indicated as depressed into the surface of the strand, but it is desirable that the indentations produced in the surface of the strand 19 be sufficiently deep so that they will not be completely filled by the pigment taken from the strip.

As used in this specification the term strand is intended to denote any strip, cord, sheet, wire, 25 rod or film which is adapted to be marked by the apparatus of this invention.

The novel features and operation of the device will be apparent from the foregoing description. While the apparatus has been shown and the 30 structure described in detail, it is obvious that this is not to be considered limited to the exact form disclosed and that changes may be made therein within the scope of what is claimed without departing from the spirit of the invention.

What is claimed is:

1. Apparatus for marking strands comprising a rotatable disc bearing raised marking indicia and a co-operating idler pulley, said apparatus being actuated by drawing the strand to be marked between said marking disc and said idler pulley in a direction normal to the axis of rotation of said disc and means actuated by the rotation of said disc effective to move a pigmented strip across the face of the marking indicia in a direction parallel to the axis of rotation of said disc while said strip is not in contact with said strand, said pigmented strip being passed between spools whose axes are normal to the axis of rotation of said disc.

2. Apparatus for marking strands comprising a rotatable cradle, marking indicia located on the periphery of said cradle, means for exerting pressure on a strand passed across the surface of said marking indicia in a direction perpendicular to the axis of rotation of said cradle, a roll of strip carried by said cradle, the strip from said roll being coated with material transferable under pressure and means operated by the rotation of said cradle for advancing said strip across the surface of said marking indicia in a direction parallel to the axis of rotation of said cradle at a time when said strip is not in contact with said strand said strip being passed between spools whose axes are normal to the axis of rotation of said cradle, the entire apparatus being actuated by the movement of said strand.

3. Apparatus for marking strands comprising a rotatable cradle and a cooperating idler pulley, said cradle carrying raised marking indicia located in the same plane as said idler pulley and means attached to said cradle for advancing a pigmented strip across the face of said marking indicia in a direction parallel to the axis of rotation of said cradle at a time when said strip is not in contact with said strand said pigmented strip

being passed between spools whose axes are normal to the axis of rotation of said cradle, the entire apparatus being actuated by the movement of said strand between said idler pulley and said marking indicia in a direction perpendicular to the axis of rotation of said cradle.

4. Apparatus for marking strands comprising a rotatable cradle, marking indicia carried by said cradle, means for exerting pressure on a strand 10 passed across the surface of said marking indicia in a direction perpendicular to the axis of rota-

tion of said cradle, means actuated by the rotation of said cradle for moving a pigmented strip across the surface of said marking indicia in a direction parallel to the axis of rotation of said cradle at a time when said strip is not in contact with said strand, said pigmented strip being passed between spools whose axes are normal to the axis of rotation of said cradle, the entire apparatus being actuated by the movement of said strand. 5

JOHN W. OLSON.
